UNITED STATES PATENT OFFICE.

FRANK B. MIEZEJEWSKI, OF ADAMS, MASSACHUSETTS.

BULLET-DEFLECTOR FOR CANNONS.

1,151,116.

Specification of Letters Patent. Patented Aug. 24, 1915.

Application filed June 1, 1915. Serial No. 31,451.

To all whom it may concern:

Be it known that I, FRANK B. MIEZEJEWSKI, a subject of the Czar of all Russians, residing at Adams, in the county of Berkshire and State of Massachusetts, have invented certain new and useful Improvements in Bullet-Deflectors for Cannons, of which the following is a specification.

This invention relates to new and useful improvements in a bullet deflector for cannons.

The primary object of this invention is the provision of a bullet deflector for ordnance such as a cannon and whereby the operator will be protected from the flying bullets of the enemy, although having a free forward view for sighting the gun.

A further object of the invention is to provide a cannon attachment in the form of a revoluble bullet shield forwardly positioned of the artilleryman's situation, the shield being operable by the artilleryman simultaneously with the gun loading, sighting and firing operations.

A still further object is to provide a movable bullet shield operable by an artilleryman and capable of deflecting any oncoming missiles although allowing visual access through the shield for sighting and firing upon the enemy.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views:—Figure 1 is a side elevation of a cannon provided with the present invention, the same being illustrated in a state of rest. Fig. 2 is a transverse sectional view taken upon line II—II of Fig. 1, and Fig. 3 is a longitudinal sectional view taken upon line III—III of Fig. 1.

The present invention although adaptable as a bullet shield for different forms of ordnance, is herein illustrated as operatively positioned upon a cannon 10 mounted upon a base 11 by means of spaced supporting legs 12.

The bullet shield is revolvably mounted upon the cannon by means of a sleeve 13

journaled thereon and a collar 14 journaled upon the cylindrical forward portion 15 of the cannon of a greatly reduced diameter, the shield consisting of two oppositely arranged obliquely positioned blades 16, V-shaped in cross section and having their forward narrower ends 17 fixed to the collar 14, while the said blades are connected adjacent their rear ends to the sleeve 13 by means of diametrically opposed brackets 18.

The sleeve 18 and collar 14 are longitudinally slidable upon their respective journaling portions of the cannon for allowing for the recoil of the gun, and opposite stop lugs 19 are provided upon the cannon forwardly of the sleeve 13 for limiting the forward movement thereof while an annular stop band 20 is positioned at the mouth 21 of the cannon for limiting the forward movement of the collar 14, it being understood that a rearward movement of the entire shield is prevented by reason of the tapering of the cannon as at 22 in the rear of the collar 14 and extending to a point substantially at the forward limit of movement of the sleeve 13 as determined by the aforementioned stop lugs 19.

A power shaft 23 is journaled through the leg supports 12 and is provided with a balance wheel 24 upon its outer end having an operating handle 25 and whereby the artilleryman at the station adjacent the breech 26 of the cannon may readily operate the said power shaft. A driven shaft 27 is also journaled through the legs 12 and has a pinion 28 upon its forwardly projecting end, which pinion is in constant mesh with the gear toothed portion 29 of the periphery of the journaled sleeve 13. The sleeve teeth are elongated for allowing the longitudinal sliding movement of the sleeve upon the cannon while the pinion 28 remains in constant mesh therewith. An idler shaft 30 is arranged between the said power and driven shafts and is provided with a pinion 31 in mesh with a gear 32 upon the power shaft 23 and is also provided with a gear 33 in constant mesh with a pinion 34 upon the driven shaft 27.

The blades 16 being of a substantially V-shaped formation and pointing forwardly, it will be seen that through the agency of the crank 25, and the gearing connections between the power shaft 23 and the journaled mounting sleeve 13 that the blades may be rapidly revolved whenever desired.

The speed of such revolutions may be varied by the artilleryman so as to obtain the desired degree of free visual access to the enemy in advance of the cannon and the artilleryman may revolve the blades with great rapidity when desired for the purpose of deflecting any flying missiles, it being understood, that the greater the speed of the shield, the more efficient the same becomes as a bullet deflector although less capable of allowing visual access therethrough. In whatever position the blades are located, even when remaining stationary, the same being gabled upon the line of merger of the opposite sloping sides of the blades, serve to deflect bullets away from the cannon and the immediate vicinity thereof. The invention thus provides a serviceable shield for protecting the lives of artillerymen during the operation of the gun and it will be noted that minor changes may be made in the invention from those herein illustrated, such for instance, as the provision of a greater number of deflecting blades and without departing from the spirit and scope of the invention as claimed.

What is claimed as new is:—

1. An attachment for cannons comprising a forwardly positioned collar and a sleeve spaced therefrom, each being revolvably journaled upon the cannon, oppositely arranged rearwardly diverging forwardly tapering blades substantially V-shaped in cross section having their forward ends secured to the said collar, diametrically positioned brackets upon the said sleeve secured to the inner faces of the said blades, and manual revolving means for the said sleeve extending adjacent the breech end of the cannon.
2. An attachment for cannons comprising a forwardly positioned collar and a sleeve spaced therefrom, each being revolvably journaled upon the cannon, oppositely arranged rearwardly diverging forwardly tapering blades substantially V-shaped in cross section having their forward ends secured to the said collar, diametrically positioned brackets upon the said sleeve secured to the inner faces of the said blades, an annular stop band for the said collar arranged at the cannon's mouth, opposite stop lugs for the said sleeve, the exterior of the cannon being tapered from the rearward limit of movement of the collar to the forward limit

of movement of the sleeve and manual revolving means for the said sleeve.

3. A bullet deflecting attachment for a cannon having a forward tapered portion forwardly terminating in a reduced cylindrical portion adjacent the mouth of the cannon, and comprising a slideable collar journaled upon the said reduced cylindrical portion forwardly of said tapered portion, a stop band for the said collar arranged at the mouth of the cannon, a slideable sleeve journaled upon the cannon rearwardly of the tapered portion thereof, opposite stop lugs for the said sleeve terminating at the inner end of the said tapered portion, oppositely arranged rearwardly flaring deflecting blades V-shaped in cross section and having their forward tapered ends secured to the said collar, diametrically oppositely arranged brackets upon the said sleeve secured to the said blades, and revolving means for the said deflecting attachment.

4. A bullet deflecting attachment for a cannon having a forward tapered portion forwardly terminating in a reduced cylindrical portion adjacent the mouth of the cannon, and comprising a slideable collar journaled upon the said reduced cylindrical portion forwardly of said tapered portion, a stop band for the said collar arranged at the mouth of the cannon, a slideable sleeve journaled upon the cannon rearwardly of the tapered portion thereof, opposite stop lugs for the said sleeve terminating at the inner end of the said tapered portion, oppositely arranged rearwardly flaring deflecting blades V-shaped in cross section and having their forward tapered ends secured to the said collar, diametrically oppositely arranged brackets upon the said sleeve secured to the said blades, supporting legs for the said cannon, elongated gear teeth upon the said sleeve, a driven shaft journaled in the said legs, a pinion upon the said shaft in constant mesh with the said sleeve gear teeth, a power shaft journaled in the said legs, opposite connections between the said power and driven shafts, a fly wheel at the rear end of the said power shaft and rearwardly of the cannon and an operating handle upon the said fly wheel.

In testimony whereof I affix my signature.

FRANK B. MIEZEJEWSKI.
